UNITED STATES PATENT OFFICE.

ARTHUR J. ADAMS, OF CHICAGO, ILLINOIS, ASSIGNOR TO FULTON MANUFACTURING COMPANY, OF CHICAGO, ILLINOIS, A CORPORATION OF ILLINOIS.

PERAMBULATOR OR GO-CART.

1,111,517.

Specification of Letters Patent.

Patented Sept. 22, 1914.

Application filed March 1, 1913. Serial No. 751,423.

To all whom it may concern:

Be it known that I, ARTHUR J. ADAMS, a citizen of the United States, residing at Chicago, in the county of Cook and State of Illinois, have invented a new and useful Improvement in Perambulators or Go-Carts, of which the following is a specification.

The present invention pertains particularly to perambulators, baby carriages or go-carts of the folding type; and the primary object of the invention is to provide improved means for automatically stretching the flexible side pieces of the body of such a structure in the operation of unfolding the structure, such means nevertheless, permitting the folding action of the cart without hindrance.

The invention is illustrated in its preferred embodiment in the accompanying drawings, in which—

Figure 1 represents a broken longitudinal sectional view of a perambulator constructed in accordance with my invention; Fig. 2, a broken plan view taken as indicated at line 2 of Fig. 1; and Fig. 3, a broken sectional view taken as indicated at line 3 of Fig. 2.

In the construction illustrated, A represents a running gear frame equipped with wheel-forks A' connected in a well understood manner by pivots 1 with wheel-brackets 2 carried by the running gear frame; B, a seat mounted on springs 3 carried by a cross-member 4 of the running gear frame, which is disposed in the plane of the front wheel brackets 2; C, a back foldably connected with the seat B, through the medium of connections 5, which need not be described in detail herein; and D, the folding superstructure of the cart, which comprises a handle 6, side-arms 7, links 8 and flexible side pieces 9.

The links 8 are connected at their lower portions, by pivots 10, to ears 11 with which the side members of the running gear frame are equipped; and the upper portions of the links are connected, by pivots 12, with the front portions of the arms 7. The rear ends of the arms 7 are connected by pivots 13 with the side members of the handle 6; and the lower ends of the side members of the handle are connected, by pivots 14, with the slightly upturned rear ends of the side members 15 of the running gear frame. The side members 15 of the running gear frame

are connected in the vicinity of the rear wheel-fork brackets 2 by a cross-bar 16 having rearwardly turned extremities 17 which are rigidly connected with the members 15. Foldable brace-links 18 connect the side members of the handle with the side members of the running gear frame in the usual manner.

At each side of the go-cart structure, yielding guide connections E connect the lower edge portions of the side flaps 9 with the running gear frame. The upper edge portion of each side flap is connected, by rivets 19, with the corresponding arm 7. Each device E preferably comprises a guide-rod 20 having its front end connected with the corresponding pivots 10; a frame 21 having its front end connected, by a pivot 22, with the side member 15 in the rear of the cross-member 16 and having its rear end turned inwardly, as indicated at 23, and provided with a perforation 24 through which the rear end of the rod 20 extends freely; a spring 25 connecting the arm 21 with the base portion 2a of the rear bracket member 2, said spring tending to throw the arm 21 downwardly until the rod 20 bears on the rear cross-member 16; and a guide-member, or loop, 26, connected with the free lower edge portion of the side flap 9 near the rear end thereof and slideable freely on the rod 20.

It will be noted that the links 8 and the handle 6 incline rearwardly when the go-cart structure is in the open condition. Hence, when the structure is folded by swinging the handle forward, the side flap 9 will be lifted until the pivot pins 12 and 13 are carried past the vertical lines extending from the pivot pins 10 and 14, after which the side flap will be lowered and finally folded. In the folding operation, the guide members or loops 26 will slide on the rods 20; and the rods 20 may be flexed or bent during that portion of the operation when the side flaps are being lifted above the position shown in Fig. 1. Any further yielding which may be necessary is permitted by the spring-held arms 21 which constitute the rear guides for the guide-rods 20.

In the operation of opening or extending the go-cart structure, the members 26 slide rearwardly on the rods 20, the same flexing and yielding action previously described taking place; and it will thus be understood that the members 26 are automatically re-

turned to the position shown in Fig. 1, and during the unfolding operation the flexible side pieces 9 are maintained in a stretched condition, and so are automatically positioned properly.

The foregoing detailed description has been given for clearness of understanding only, and no undue limitation should be understood therefrom, but the appended 10 claims should be construed as broadly as permissible in view of the prior art.

What I regard as new and desire to secure by Letters Patent is—

1. In a perambulator, the combination of 15 a running gear frame, a folding superstructure mounted thereon equipped with flexible side pieces, and yielding guide connections between the lower portions of said flexible side pieces and the running gear frame, including longitudinally disposed yielding guides and means carried by the flexible side pieces and slidably engaging said guides.

2. In a perambulator, the combination of 25 a running gear frame, a handle pivotally connected to the rear portion thereof and adapted to fold forwardly thereon, arms pivotally connected with said handle, links pivotally connected with the front portions 30 of said arms and also pivotally connected with the running gear frame, flexible side pieces depending from said arms, longitudinally-disposed yielding guide members carried by the running gear frame, and means 35 connected with the lower portions of said flexible side pieces and slidably engaging said guide members.

3. In a perambulator, the combination of 40 a running gear frame, a foldable superstructure mounted thereon and equipped with flexible side pieces, rods pivotally supported at their front portions near the plane of the running gear frame, yieldingly-held guide arms engaging the rear portions of said 45 rods, and means carried by the lower portions of the flexible side pieces and slidably engaging said rods.

4. In a perambulator, the combination of 50 a running gear frame, a foldable superstructure thereon equipped with flexible side pieces, longitudinally extending rods mounted at their front ends on pivots carried by the running gear frame, arms connected at their front portions to the running gear

frame near the rear wheel-forks and having 55 their rear portions equipped with guides engaging said rods, and guide members attached to the lower portions of said flexible side pieces and slidably engaging said rods.

5. In a perambulator, the combination of 60 a running gear frame, a handle pivotally connected with the rear portion thereof and adapted to fold forwardly thereon, arms pivotally connected at their rear ends with 65 said handle, links pivotally connected with the front ends of said arms and also pivotally connected with the running gear frame, flexible side pieces depending from 70 said arms, guide-rods pivotally connected at their front portions with the running gear frame, spring-held arms connected with the rear portion of the running gear frame and having guides for the rear portions of 75 said rods, and means connected with said flexible side pieces and slidably engaging said rods.

6. In a perambulator, the combination of 80 a running gear frame, a handle pivotally connected with the rear portion thereof and adapted to fold forwardly on the running gear frame, arms pivotally connected with 85 said handle, links pivotally connecting the front ends of said arms with the running gear frame, flexible side pieces depending from 90 said arms, longitudinally-disposed, yieldingly-held guide-rods connected with the running gear frame, and loops connected with the rear lower portions of said flexible side pieces and slidably engaging said rods.

7. In a perambulator, the combination of 95 a running gear frame, a handle pivotally connected with the rear portion thereof and adapted to fold forwardly on the running gear frame, arms pivotally connected with said handle, links joining the front ends 100 of said arms to the running gear frame, flexible side pieces depending from said arms, rods pivotally connected at their front portions with the running gear frame, spring-held arms having guide portions receiving the rear ends of said rods, and guide loops connected with the lower rear portions of said flexible side pieces and slidably engaging said rods.

ARTHUR J. ADAMS.

In the presence of—

J. G. ANDERSON,
O. C. AVISUS.
